GUN TYPE OIL BURNER APPARATUS WITH
AIR THROTTLING AND WHIRLING MEANS

John Gordon Kaveny, Montclair, N. J.

Application November 24, 1947, Serial No. 787,805

4 Claims. (Cl. 158—76)

1

This invention relates to improvements in oil burners used for firing furnaces, and especially adapted for use in firing house heating furnaces.

The invention has for an object to provide, in oil burner apparatus of the forced draft type, a novel and more efficient means for controlling the volume and movement of air to and past an oil discharging nozzle of the burner, whereby to attain highly efficient oil atomizing effect for the production of a primary combustible admixture of oil and air.

The invention has for another object to provide novel means for supplying auxiliary air to the combustible mixture discharged from the burner, including means for controlling the volume of such supplied auxiliary air, whereby to better assure complete combustion of the oil constituent of the ignited primary mixture which is discharged from the burner.

Other objects of this invention, not at this time more particularly enumerated, will be understood from the following detailed description of the same.

Illustrative embodiments of this invention are shown in the accompanying drawings, in which:

Fig. 1 is a side elevational view of oil burner apparatus made according to the invention; Fig. 2 is a top plan view of the same; and Fig. 3 is an elevational view of the discharge end thereof.

Fig. 4 is a fragmentary longitudinal horizontal sectional view, taken on line 4—4 in Fig. 1, but drawn on an enlarged scale; and Fig. 5 is a transverse sectional view, taken on line 5—5 in Fig. 4, but drawn on a still further enlarged scale.

Fig. 6 is a top plan view, similar to that of Fig. 2, but showing a modified embodiment of the invention; this view being drawn on a reduced scale.

Similar characters of reference are employed in the above described views, to indicate corresponding parts.

Referring to the drawings, the oil burner apparatus according to this invention, in one illustrative embodiment thereof, comprises a blower housing 10, having at one side thereof an air intake means 11. Said housing is suitably supported, as e. g. by a pedestal base 12. Leading from the housing 10 is a tubular gun shell 13. Rotatable within said housing is a driven fan or blower 14 which draws air from the atmosphere through the air intake means 11, and discharges the same outwardly through the tubular gun shell 13, all in manner already known to the art. Mounted in connection with the housing 10 is an electric motor 15 which is adapted to drive the fan or blower 14.

Suitably connected with the housing 10 and its gun shell 13 is an oil supply pipe 16, the same being disposed to extend axially outward through the interior of said gun shell 13. The oil supply

pipe 16 terminates at its outer end in an oil discharge nozzle 17, which lies within the outwardly open discharge mouth of the gun shell 13. Fixed within the gun shell passage behind the discharge nozzle 17 is a stationary turbulator or air whirling means 18, the same comprising angularly pitched radial vanes 19 which surround the oil supply pipe 16 so as to intersect the annular space between the latter and the surrounding walls of the gun shell 13.

Mounted across the interior of the gun shell 13, inwardly of said stationary turbulator or air whirling means 18—19, is a combined manipulatable air throttling and turbulator or air whirling means, by means of which the volume of air discharged through the gun shell for primary admixture with oil discharged from the nozzle 17 may be regulated, while nevertheless imparting a desired turbulent whirling movement to the discharging air, which movement being continued and augmented by the stationary turbulator or air whirling means 18—19, produces a gyratory movement of outgoing air about the oil discharge nozzle 17, whereby said air encounters the spray of oil discharged from the latter with high atomizing effect and resultant intimate intermingling of the atomized oil particles with said air, thus producing a highly combustible mixture.

The combined adjustable air throttling and turbulator or whirling means comprises, essentially, a plurality of radial vanes supported subject to rotative movement about their axes, whereby to vary both the pitch thereof and the spread thereof relative to the transverse plane of the passage of the gun shell 13, and manipulatable means for producing such adjusting rotative movements of said vanes. An illustrative structure involving these essentials, as shown, comprises a hub member 20 fixed upon the oil supply pipe 16, and a plurality of radial vanes 21 which extend from said hub member across the annular space between the oil supply pipe and the walls of the gun shell 13. Each vane 21 is provided at its inner end with an axially extending journal stud 22 which is pivotally journaled in the hub member 20. One of said vanes 21 is provided at its outer end with a trunnion 23 which is journaled in and through the wall of the gun shell 13, and affixed on the exterior end 50 of said trunnion 23 is a manipulatable knob or finger piece 24 by which said vane can be manually rotated about its longitudinal axis.

Rotatably mounted on the oil supply pipe 16, adjacent to one end of the hub member 20, is a vane rotator cam 25. This cam 25 is provided in its external marginal portions with indenting notches 26 which correspond in number and spacing to the number and spacing of the vanes 21; said notches being adapted to respectively straddle the lower end portions of the respective

vanes at points offset from the pivotal connections thereof with the hub member 20. Said cam 25 is held in the described operative relation to the hub member 20 and vanes 21 by a collar 27 which is also affixed to the oil supply pipe 16. Said collar possesses an inner end portion 28 of reduced diameter so as to provide clearance space for accommodation of the rotative adjusting movements of the vanes about their pivoting journal studs 22.

In the operation of the described combined air throttling and whirling device, whereby to adjust the vanes for change of pitch with air stream throttling effect, the knob or finger piece 24 is turned in desired direction to thereby turn the vane 21 with which it is connected; the turning of which rotates the cam 25 so as to cause the latter to transmit corresponding movements to the other vanes. By such manipulation, the vanes 21 may be turned toward or from a transverse plane intersecting the passage of the gun shell 13, whereby to enlarge or reduce the open area between the vanes, so as to increase or decrease the volume of air flowing outwardly through the passage of said gun shell 13 and past the oil discharge nozzle 17, as the case may be, with desired air flow throttling effect. The pitch angle of the vanes, although at the same time subject to variation, will, nevertheless, deflect the air flowing past the vanes so as to impart thereto a desired gyratory or whirling turbulence as it flows toward the oil discharge nozzle 17; which gyratory or whirling turbulence will be further assured as the discharged air moves past the pitched vanes 19 of the stationary turbulator or air whirling means 18 which is located adjacently behind said oil discharge nozzle 17.

Mounted on and about the discharge end of the gun shell 13 is an auxiliary air discharge head 30 from which air supplied thereto is discharged into the ignited primary fuel mixture issuing from the gun shell, thereby to supply additional oxygen to the burning fuel mixture as an aid to thorough, complete and substantially smokeless combustion of the inflammable oil constituent of said mixture. This auxiliary air discharge head comprises a hollow annular body closed at its rear end by a back wall 31 and provided with side walls 32 which converge upon the discharge end of the gun shell 13, so as to form, in conjunction with the periphery of the latter, an annular discharge mouth 33, from which auxiliary air supplied to the interior of the discharge head is discharged in an annular stream adapted to convergently impinge upon and embrace the burning fuel mixture which issues from the gun shell, so as to mingle with said burning fuel mixture and thus supply additional combustion supporting oxygen to the latter. Preferably, said discharge head 30 is internally constructed to provide means for imparting a whirling or gyratory turbulence to the auxiliary air discharged therefrom, whereby to further assure efficient admixture of the auxiliary air with the burning fuel mixture. The means for thus imparting whirling or gyratory turbulence to the discharged auxiliary air comprises a plurality of circumferentially spaced internal helical vanes 34 which extend from the side walls 32 of the discharge head and between said side walls and the end portion of the gun shell inwardly of the discharge mouth 33.

Means is provided for supplying auxiliary air to the interior of the discharge head 30, includ-

ing means for adjustably regulating the volume thereof. One arrangement of means for this purpose, as shown in Figs. 1, 2 and 4 more particularly, comprises a chambered air by-pass extension 35 which is connected with the housing 10 to project externally therefrom, and which communicates with the interior of said housing 10 through a port 36 with which the adjacent wall of the latter is provided. A tubular auxiliary air supply duct 37 is connected by its rear end in communication with said by-pass extension 35. This duct 37 extends to the discharge head 30 so that its forward end enters through the back wall 31 of the latter to communicate with the interior of the discharge head. The means for regulating the volume of auxiliary air delivered to the discharge head 30 through the by-pass extension 35 and duct 37 comprises an adjustable throttling shutter 38 which is slidably supported on the interior side of the wall of the housing 10 for movement relative to and across said port 36, so as to diminish the area thereof at will. Said throttling shutter 38 is manipulatable from the exterior of the housing 10, and to this end a finger piece 39 is provided to project outwardly from the throttling shutter through a slot 40 with which the housing wall is provided.

In practice, the oil burner apparatus of this invention is provided with suitable, and usually electrically controlled, fuel mixture ignition means disposed at the discharge end of the gun shell 13 adjacent to the oil discharge nozzle 17. Showing of such ignition means has been omitted from the drawings, since its application and use in connection with oil burner apparatus is well known to the art.

In the operation of the oil burner apparatus of this invention, oil is supplied to the oil discharge nozzle 17 through the supply pipe 16 by a suitable pump means (not shown) which is also well known to the art. Primary air is discharged by the blower or fan 14 for outward passage through the gun shell 13 with atomizing effect upon the oil discharged from the oil discharge nozzle 17, whereby to produce a combustible fuel mixture subject to ignition and discharge from said gun shell. The volume of primary air so delivered through the gun shell is subject to regulation by adjusting the vanes 21 of the combined air throttling and whirling device in the manner already above described. The flow of auxiliary air is also derived from the operation of the blower or fan 14, part of the delivered air output of which is by-passed through the port 36 into the by-pass extension 35, to flow thence through the duct 37 into the auxiliary air discharge head 30, to discharge from the latter in the manner and for the purposes as hereinabove set forth. The volume of auxiliary air flow may be regulated by throttling the port 36 by means of the manipulatable shutter 38.

Referring to Fig. 6, I have shown therein another arrangement of means for supplying auxiliary air to the discharge head 30, which is, however, comprehended by the broad aspects of this invention, the same comprising a small independent blower or fan 41 mounted in connection with motor 15, with which the housing 10 is equipped, so as to be driven from the exterior end of the motor armature shaft, the interior end of which drives the main fan or blower 14. Connected with said blower or fan 41, to receive the air discharged thereby, is a conduit or duct 42 which leads to and into the discharge head 30, whereby to deliver auxiliary air thereto for dis-

charge therefrom. The conduit or duct 42 is equipped, at a suitable location intermediate its ends, with a pivoted damper or throttle means 43 disposed across the interior thereof. Said damper or throttle means 43 is provided with an external finger piece or handle means 44 by which it can be manipulated for regulation of auxiliary air delivered through the conduit or duct 42 to the discharge head 30.

While I have shown and described illustrative embodiments of features of the present invention, it will be understood that various modifications may be made therein without departing from the scope of the invention as defined in the hereinafter claims.

Having now described my invention, I claim:

1. In an oil burner having a blower housing and an outwardly open tubular gun shell extending therefrom with an oil supply pipe extending axially in the latter and terminating in an oil discharge nozzle at the outer open end thereof, the combination with said gun shell of an adjustable air throttling and whirling means mounted across the interior thereof comprising a hub member fixed on the oil supply pipe, a plurality of radial vanes pivotally supported by said hub member for rotative adjusting movements about their longitudinal axes, manipulatable means extending from the outer end of one of said vanes through the gun shell wall, whereby said latter vane can be rotatively adjusted, and means cooperative with all of said vanes for transmitting the adjusting movement of the manipulated vane correspondingly to the remaining vanes.

2. In an oil burner having a blower housing and an outwardly open tubular gun shell extending therefrom with an oil supply pipe extending axially in the latter and terminating in an oil discharge nozzle at the outer open end thereof, the combination with said gun shell of an adjustable air throttling and whirling means mounted across the interior thereof intermediate its ends, said adjustable air throttling and whirling means comprising a hub member fixed on the oil supply pipe, a plurality of radial vanes pivotally supported by said hub member for rotative adjusting movements about their longitudinal axes, manipulatable means extending from the outer end of one of said vanes through the gun shell wall, whereby said latter vane can be rotatively adjusted, and a cam means rotatable about the axis of said oil supply pipe, said cam means having indented marginal portions to embrace inner end portions of all said vanes at points laterally offset relative to their longitudinal axes of rotative movement, whereby adjusting rotative movement of the manipulated vane is transmitted to said cam means and by it to the remaining vanes.

3. In an oil burner having a blower housing and an outwardly open tubular gun shell extending therefrom with an oil supply pipe extending axially in the latter and terminating in an oil discharge nozzle at the outer open end thereof, the

combination with said gun shell of an adjustable air throttling and whirling means mounted across the interior thereof intermediate its ends, said adjustable air throttling and whirling means comprising a hub member fixed on the oil supply pipe, a plurality of radial vanes pivotally supported by said hub member for rotative adjusting movements about their longitudinal axes, and a trunnion extending axially from the outer end of one of said vanes, said trunnion being journaled in and through the wall of said gun shell, a finger piece on the external end of said trunnion by which said latter vane can be manipulated for rotative adjustment, and means cooperative with all said vanes for transmitting the adjusting movement of the manipulated vane correspondingly to the remaining vanes.

4. In an oil burner having a blower housing and an outwardly open tubular gun shell extending therefrom with an oil supply pipe extending axially in the latter and terminating in an oil discharge nozzle at the outer open end thereof, the combination with said gun shell of an adjustable air throttling and whirling means mounted across the interior thereof intermediate its ends, said adjustable air throttling and whirling means comprising a hub member fixed on the oil supply pipe, a plurality of radial vanes pivotally supported by said hub member for rotative adjusting movements about their longitudinal axes, a trunnion extending axially from the outer end of one of said vanes, said trunnion being journaled in and through the wall of said gun shell, a finger piece on the external end of said trunnion by which said latter vane can be manipulated for rotative adjustment, and a cam means rotatable about the axis of said oil supply pipe, said cam means having indented marginal portions to embrace inner end portions of all said vanes at points laterally offset relative to their longitudinal axes of rotative movement, whereby adjusting rotative movement of the manipulated vane is transmitted to said cam means and by it to the remaining vanes.
